TYPE HOLDING CHASE

Frank H. Poeppelmeier, Euclid, Ohio, assignor to
Set-O-Type Manufacturing Company, Cleve-
land, Ohio, a corporation of Delaware

Application October 20, 1932, Serial No. 638,702

10 Claims. (Cl. 101—375)

This invention relates to a flexible type chase of the character which is adapted to carry a page form of individual type of low height and grooved in its opposite sides and mounted between parallel ledges on the chase. Such a chase may be mounted on a rotary segment or on a flat support for printing, and may be filed away in substantially flat form.

The general object of the invention is to provide a chase of the character described so constructed that it may be very economically manufactured and will be efficient in service. The ability for easy assemblage of the type into the chase, for the proper positioning and holding of the type therein, and for the mounting of the chase on a printing drum or flat support are also features of my invention.

To the above end, I have provided a chase made up of a series of sheet metal members bent into channel shape with their edges projecting toward each other and then downwardly to provide split tubes formed to receive and effectively hold type grooved on its opposite sides, these tubes being placed side by side and caused to form a blanket by flat strips which pass through slits in the side walls of the tube adjacent the base, so that the strips contact with the bases.

Beyond the outside tubular holders of the blanket, I provide suitable means to engage such extreme members and hold the entire set of tubes compactly, one against the other. This compacting means may comprise a cross-bar riveted to the strips and preferably provided with graduations to aid in the proper location of the type in the chase.

In place of the graduated cross-bar riveted to the longitudinal strips I may, if desired, form stops by turning inwardly the end portions of the strips to abut the outer sides of the two extreme tubular holders, this feature being particularly useful where a small chase is made up adapted to be placed on a block and mounted as a part of a flat printing form.

To assist in the ready mounting of the type within the channels of the chase, I taper the extreme ends of the inwardly and downwardly projecting flanges of the holders.

I provide slits through the side walls of the holders adjacent the ends and a considerable distance above the bottom, these slits in the respective holders aligning with each other to provide a passageway transversely of the holders and beyond the region to be occupied by the type; this passageway is thus adapted to receive a thin strip of metal passed through the openings and serv-

ing as a stop to the different lines at that edge of the form.

My invention comprises the means by which I carry out the above features, or any of them, as hereinafter more fully explained and as summarized in the claims.

In the drawings, Fig. 1 is an end elevation of my flexible chase in its curved form suitable for mounting on a semi-circular segment; Fig. 2 is a plan of the same in flattened form ready for mounting on a flat bed or for filing; Fig. 3 is a bottom plan of a portion of the chase in flattened form; Fig. 4 is a cross-section, on enlarged scale, on the line 4—4 on Fig. 2; Fig. 5 is a section at right angles to Fig. 4, as indicated by the line 5—5 on Fig. 4; Fig. 6 is a plan of a small size flat chase suitable for mounting as an insert; Fig. 7 is a cross-section on the line 7—7 of Fig. 5; Fig. 8 is a perspective, partly in section of one of the tubular holders; Fig. 9 is a plan of the end portion of one of the holders. Intermediate portions are omitted in Figs. 1, 2 and 6 for simplicity of illustration.

The tubular type holding members 10, constituting the body of my chase, are of the form shown in cross-section in Figs. 4 and 7 and in perspective in Fig. 8. These tubular members have flat bases 11 from which rise sides 12 at right angles to the base, and at the top of these sides are inwardly extending ledges 13, from the inner edges of which flanges 14 depend toward the base. This makes in effect a split tube substantially rectangular in cross-section with a slot along the top and guiding edges on opposite sides of the slot, which, by reason of the down-turned portions 14, have a materially greater up and down dimension than the thickness of the metal. Such a tube is adapted to receive and effectively hold type of the form indicated at A in Fig. 4, such type being on the market for use in multi-graph machines.

To enable the type to be readily slid into the channels of the tubes, I taper the ends of the top ledges 13 and the downturned flanges 14 as shown at 16 and 17 in Figs. 5, 8 and 9.

The various tubular members 10 are placed side by side in contact with each other and are held in place by strips of metal 20, which pass through slits 18, formed in the side walls 12 of the members directly above the base, so that each strip 20 lies in contact with the bases 11 of the members, as shown in Figs. 4 and 7.

The collection of tubular members mounted on the strips 20 is preferably held permanently com-

pacted to form an effective blanket. I may accomplish this by securing to the strips bars 30 extending across them and bearing against the outer side walls of the extreme tubular members. This is the construction illustrated in Figs. 1-4. The bar 30 is there shown as connected to the strip 20 by suitable rivets 31.

When the bars 30 are employed I avail myself of them to provide a convenient scale to assist in the location of the type in desired position. This scale is shown as effected by graduations 32, formed on the upper surface of the bars. This is very useful for tabular work, enabling the spacing of the type, after it has been placed in the chase, into columns, as desired.

The strips 20 may be formed with means for attachment to a segment or other support. To this end I have shown these strips at one end as bent back on themselves to provide hooks 22, and at the other end as having slots 23, though other means of attachment may be used.

In place of holding the tubular members on the strips compacted by cross bars, I may effect the result by bending back the upper portion of the strips themselves, as indicated in Figs. 6 and 7. In this case, the stiff bent-over end 25 of the strip 20 abuts the outer wall 12 of the endmost split tube 10 and thus locks the construction into a compact blanket. This form is particularly suitable for comparatively small insert work where it is desirable to make up a chase adapted to carry a number of lines of type, the whole to be mounted in a larger printing form; though, if desired, this same method of binding the strips to the tubular holders might be employed in large-sized chases.

The clearance of the strips 20 with the slits 18 is exaggerated in Figs. 4 and 7 of the drawings. In practice, the openings 18 through the side walls are of such size that the strips 20 easily fit the openings. This enables the convenient assemblage of the parts to form the blanket and insures the tubular members being effectively held in position against shifting in any direction.

It is desirable to provide means to form a stop at one end of the chase to cause the page form to align at that edge. For this purpose I make slits 19 through the side walls 12 of the tubular members near the ends thereof and a considerable distance above the base. These slits are located beyond the region of the tube occupied by the type, and thus form an unobstructed passageway leading from one end of the blanket to the other. Through this passageway I may pass the thin, flat, flexible strip 40 (Figs. 2, 5, 6 and 7). This strip is preferably tapered at its end and is pliable, and there is sufficient clearance so that it may be readily shoved into place.

If the stopping strip 40 is used only on one edge of the chase, that is, the edge corresponding to the left-hand edge of a printed page, where the beginnings of the type lines align, this strip may be left in the chase as a permanent stop. At the other side of the page, unless the matter is justified, the lines will end in various regions and may be stopped by inserted plugs in the usual manner. When the matter is to be justified a strip may be inserted at the other side of the chase, after the type is mounted thereon, and form a straight single stop at that edge.

I claim:

1. The combination of a series of line holders held in compacted relationship, side by side, each line holder having upwardly extending side walls,

narrow inwardly extending top portions leaving a space between them, and downwardly extending flanges at the inner edges of the top portion.

2. The combination of a series of line holders side by side, each line holder comprising a split tube having a base, side walls and narrow top portions extending inwardly from the side walls and then turning downwardly to provide guiding edges spaced apart and of greater effective height than the thickness of the metal, and holding devices passing through a succession of line holders.

3. A type chase comprising a series of channel members mounted side by side and transverse holding members engaging the channel members, each channel member having ledges at the top and depending edge flanges at the inner edges of the ledges, there being space between the depending flanges and space between the lower ends of the flanges and the base of the channel member.

4. A type chase comprising a series of split tubes mounted side by side, each substantially rectangular in cross-section, each tube having at its top inwardly projecting ledges terminating in downwardly extending flanges projecting into the tube, the ends of the ledges being tapered.

5. A type chase comprising a series of split tubes mounted side by side, each tube having at its top inwardly projecting ledges terminating in downwardly extending flanges projecting into the tube, the ends of the ledges and flanges being tapered.

6. A type chase comprising a series of tubular type holders, each comprising a split tube of substantially rectangular form in cross-section, the sides of adjacent tubes being contiguous, slits formed through the sides of the tubes adjacent their bottoms, strips passing through registering slits of the tubes and bearing against the bottoms, and means mounted on the strips for preventing the tubes shifting on the strips when the chase is unmounted.

7. A type chase comprising a series of channel members having inwardly projecting ledges at the top and spaced apart to provide a channel for the reception of the type shanks with the overhanging head of the type resting on the ledge, and strips passed through the channel members above their bases, bars extending lengthwise of the channel members, and engaging the outermost ones and secured to the strips to hold the bars in compacted relation, whether the chase is mounted or unmounted, the strips extending beyond the bars to provide means for mounting the chase.

8. A type chase comprising a series of split tubes of approximately rectangular cross-section adapted to rest on their bases on a supporting member, and adapted to carry type in longitudinal openings in their top, slits through the side walls of the tubes just above the bases, and strips passing through the slits and bearing against the bases and having provision at its ends for attachment to a supporting member, and means for locking the tubes in place on the strips, to retain the chase compacted whether mounted or unmounted.

9. The combination of a series of line holders side by side, each line holder comprising a split tube with side walls connected by a continuous substantially flat base adapted to engage a support and a longitudinally slotted top, slits through the side walls of the tube and strips ex-

tending through the slits and engaging a continuous portion of said base.

10. A type chase comprising a series of split tubes having substantially flat bases and side walls having inwardly projecting ledges at the top spaced apart to provide a channel for the reception of type with their shanks between the ledges

and their overhanging heads resting on the ledges, strips passed through the side walls and engaging the bases of the tubes and transverse bars extending lengthwise of the channel member and each permanently secured to the strips and bearing against the outermost tubular members.
